UNITED STATES PATENT OFFICE

ALBERT S. MENSIK, OF CHICAGO, ILLINOIS

SCREEN FRAME

Application filed June 5, 1929. Serial No. 368,471.

This invention relates to improvements in window screens and embraces a screen frame adapted to be pivotally mounted along one of its longitudinal edges in a window casing and provided with mechanism associated with the window frame and the screen frame to facilitate mounting of the screen frame and latching of the same from the interior.

It is an object of this invention to provide a window screen frame constructed of interfitting inner and outer frame sections between which the screening is adapted to be clamped.

It is also an object of this invention to provide an improved screen frame having a sleeve integrally formed along one of the longitudinal members thereof to carry pivot pins for pivotally mounting the screen frame in a window frame.

It is a further object of this invention to provide an improved screen frame adapted to be pivotally mounted in a window frame and having a shiftable latch plate mounted on the inner side of the frame adapted to be moved into latching engagement with a latch plate secured to the window frame.

It is furthermore an object of this invention to provide an improved screen frame having pivot pins engaged in the end of one of the longitudinal members of the frame to facilitate pivotal mounting of the screen frame in a window frame by means of an improved bar and bracket arrangement mounted on the sill member of the window frame.

It is an important object of this invention to provide an improved screen frame adapted to be readily mounted in a window frame to swing outwardly on a vertical axis and having an improved bearing block for the reception of the lower pivot pin of the screen frame, with said bearing block adapted to be slidably mounted in position in a bracket secured to the window frame sill to hold the screen frame in proper position to permit latching of the screen frame from the interior by means of an improved shiftable latch plate positioned for coaction with an apertured plate secured to one of the uprights of the window frame.

Other and further important objects of this invention will be apparent from the disclosures in the specification and the accompanying drawings.

This invention (in a preferred form) is illustrated in the drawings and hereinafter more fully described.

On the drawings:

Figure 1 is a fragmentary perspective view of the exterior of a building wall and a window frame therein having associated therewith an improved screen frame embodying the principles of this invention.

Figure 2 is a slightly enlarged inside elevational view of the improved screen frame removed from the window frame and illustrating the screen frame latching mechanism.

Figure 3 is an enlarged fragmentary perspective view of a portion of the window frame sill having mounted thereon an improved bracket and bar for the support of the lower pivot pin of the screen frame.

Figure 4 is an enlarged perspective view of the mounting plate for the upper hinge pin of the screen frame.

Figure 5 is an enlarged vertical sectional view taken through the window frame on line V—V of Figure 1.

Figure 6 is a fragmentary horizontal sectional view of the screen frame taken on line VI—VI of Figure 2.

Figure 7 is an enlarged perspective view of the latch plate removed from the screen frame.

Figure 8 is an enlarged perspective view of the bearing block used for supporting the lower pivot pin of the screen frame.

Figure 9 is an enlarged fragmentary detail section of the latch mechanism taken on line IX—IX of Figure 2.

Figure 10 is a fragmentary elevational view of one corner of a modified form of screen frame illustrating an improved angle corner brace for joining two of the members of the screen frame.

Figure 11 is an enlarged detail section of the modified form of screen frame taken on line XI—XI of Figure 10.

As shown on the drawings:

The reference numeral 1 indicates a wall of

a building having an opening therein in which a window frame or casement is mounted. The window frame comprises vertical side sills or upright frame members 2 and 3 connected at their upper ends by a horizontal cross member 4. The lower ends of the frame members 2 and 3 are connected by means of a sill 5 provided with a sill extension 6.

Securely mounted on the middle portion 10 of the inner face of the casement sill member 3 is a latch plate 7 provided with a slot or opening 8 which communicates with a slot or recess 9 cut in the casement sill member 3 for the reception of a locking member hereinafter more fully described.

Mounted by means of screws or other suitable means upon the under surface at one end of the upper horizontal member 4 of the window casing is a bearing plate 10 provided 20 with a pair of screw receiving apertures 11 (Figure 4) to facilitate mounting of the plate. The bearing plate 10 is also provided with a bearing opening 12 to receive the upper bearing pin or stud 13 which projects from the 25 upper end of a tube or sleeve 14 which is integrally formed by rolling one margin of the flange forming a part of one of the longitudinal members forming a part of an outer channel cross sectioned screen frame 15.

30 The improved screen proper comprises the outer channel cross sectioned metal screen frame 15 and an inner channel cross sectioned metal screen frame 16 which telescopes or fits into the outer screen frame 15 as indicated in Figures 6 and 9 and stretches a wire screening 17 tightly in position with the margins of the wire screening clamped between the two interfitting screen frames 15 and 16. The two screen frames 16 and 40 15 are secured together by means of screws, bolts or other suitable means.

Secured in the lower end of the screen hinge tube 14 is a lower hinge pin or stud 18 which is adapted to be engaged in a socket or opening 19 provided in a bearing block 20. The bearing block 20 is slidably engaged in a guide channel 21 integrally formed on an angle bracket 22 secured by means of screws 23 or other suitable means upon one end of 50 the casement sill 5 as clearly illustrated in Figure 3. The bearing block 20 is provided with an opening 24 for the reception of a retaining screw 25 to permit the bearing block when in the position illustrated in Figure 3 to be screwed in place in the guide channel 21 to afford a bearing for the lower pivot pin 18.

In mounting the improved screen in position the upper pivot pin 13 is first engaged 60 in the bearing opening 12 of the plate 10 after which the lower bearing block is moved into the dotted line position illustrated in Figure 3 to permit the lower pivot pin 18 to be engaged in the opening 19 of the bearing block 20 after which said bearing block is

70 moved into the full line position of Figure 3 and secured in place by means of the retaining screw 25. The improved screen is thus mounted in a hinge form in the window casement or frame with the outer screen frame 15 positioned to the outside of the window.

Shiftably mounted on the middle portion of one of the longitudinal members of the inner screen frame 16 is a screen latching device comprising a plate 26 one longitudinal margin of which is bent outwardly at right angles to afford a flange 27 the margin of which is bent at right angles to provide a latch flange or locking plate 28 adapted to be moved into latching engagement with the slotted frame plate 7. The guide or mounting plate 26 of the latch device is provided with a pair of inclined slots 29 (Figure 7) through which a pair of mounting screws 30 project. Integrally formed on the 80 upper end of the mounting plate 26 of the latching device is a finger piece or angle member 31 to facilitate a shifting operation of the latching device. When the latching device is in the full line position illustrated 90 in Figure 2 the latching plate 28 is in released or unlocked position as shown in Figure 9 and is out of engagement with the slot 8 of the plate 7. The screen is thus permitted to be swung outwardly on the 95 pivot pins 13 and 18. When the screen is moved into closed position within the window casing it is adapted to be locked in place by shifting the latching device by means of the finger piece 31 downwardly into the 100 dotted line position of Figure 2 thereby projecting the latching plate 28 into the slot 8 of the plate 7 to hold the screen locked in position.

105 Figures 10 and 11 of the drawings illustrate a modified form of screen wherein a wire screening 31 is clamped in stretched position between two interfitting channel cross sectioned screen frames each of which is constructed of a pair of longitudinal channel cross sectioned sills 32 and a pair of channel cross sectioned horizontal or connecting members 33. The longitudinal frame members 32 and the transverse frame members 33 are connected together by means of 110 a pair of interfitting channel cross sectioned corner plates or unions 34 and 35. The corner plates 35 are provided with integral tongues or lips 36 which are bent at right angles to the plates 35 and project upwardly 115 through slots or openings in the corner plates 34 and are bent over to securely hold the corner plates 34 and 35 rigidly connected together to form a corner for the screen frame.

120 It will of course be understood that many changes may be made and numerous details of construction may be varied through a wide range without departing from the principles of this invention, and it is therefore not pur- 125 130

posed limiting the patent granted hereon otherwise than necessitated by the prior art.

I claim as my invention:

1. The combination with a window frame, 5 of a screen, pivot pins projecting from the ends at one side of said screen, a bearing plate secured to the upper portion of the window frame to receive one of said pivot, pins, a bracket secured to the sill of the window frame, a bearing block adjustably mounted in said bracket for the reception of the second bearing pin of the screen, a slotted plate mounted on one of the sill members of the window frame, and a latching device 10 adjustably mounted on the screen for coaction with said slotted plate to hold the screen locked in closed position.

2. The combination with a window frame, 20 of a screen, an apertured bearing plate secured in the window frame, a pivot pin projecting from the upper end of the screen and pivotally engaged in said apertured bearing plate, a bracket secured to the sill member of the window frame and having a guide 25 channel forming a part thereof, a bearing block slidably mounted in said guide channel, a lower bearing pin projecting from the lower end of the screen and projecting into the apertured bearing block to pivotally support the screen in the window frame, and means for securing the bearing block in a set position with respect to the bracket guide channel.

3. The combination with a window frame, 35 of a screen pivotally mounted therein, a slotted plate secured to the window frame, and a latch member adjustably mounted on the screen for coaction with said slotted plate to hold the screen locked in position within 40 the window frame.

4. A window screen comprising a screen frame, screening stretcher into position therein, hinge pins projecting from the ends of said screen frame, an apertured bearing 45 plate for receiving one of said hinge pins, a guide bracket, and an apertured bearing block slidably mounted in said guide bracket for the reception of the lower pin of said screen.

5. A window screening device comprising a screen frame, a hinge tube integrally formed thereon, hinge pins projecting from the ends of said hinge tube, bearing members for receiving said hinge pins, a slotted 55 plate adapted to be mounted in a stationary position, and a shiftable latch member mounted on the screen frame adapted to be moved into locking engagement with the slotted plate for holding the screen in a closed position when mounted in a window frame.

6. The combination with a window screen, 60 of pivot pins mounted thereon, an apertured bearing plate adapted to be secured in a window frame to receive one of said pins, a bracket secured on the window frame sill and

having a guide channel therein, and a bearing block for receiving the other of said pins and adapted to be slidably pushed into position to afford a suitable lower bearing for the screen.

7. The combination with a window screen, 70 of pivot pins projecting from the ends thereof, a bearing member for receiving the upper pivot pin, a bracket for supporting the lower end of the screen, a guide channel integrally formed on said bracket, a bearing block slidably mounted in said guide channel and having an opening therein for receiving the lower screen pin, and means for securing the bearing block in a set position of 75 adjustment in said guide channel after the screen has been mounted in position.

8. The combination with a window screen, 80 of pins projecting from the ends thereof to facilitate mounting of the screen, bearing 85 members for receiving said pins and adapted to be mounted in a window frame, a slotted plate adapted to be mounted in the window frame, and a shiftable latch member on said screen adapted to be moved into latching engagement with said slotted plate to latch the screen in a closed position releasable only 90 from the interior.

9. The combination with a window frame, 95 of a screen, and means for pivotally mounting said screen in the window frame and comprising an apertured upper bearing plate and a lower bearing device consisting of a bracket provided with an integral guide channel and an apertured bearing block 100 adapted to be secured to the guide channel after the screen has been properly positioned within the window frame.

In testimony whereof I have hereunto described my name at Chicago, Cook County, 105 Illinois.

ALBERT S. MENSIK.
